UNITED STATES PATENT OFFICE.

GEORGE W. BEARDSLEE, OF BROOKLYN, NEW YORK, ASSIGNOR TO
WILLIAM F. JOBBINS, OF EAST ORANGE, NEW JERSEY.

ELECTRIC-ARC LAMP.

SPECIFICATION forming part of Letters Patent No. 270,725, dated January 16, 1883.

Application filed May 20, 1882. (No model.)

To all whom it may concern:

Be it known that I, GEORGE W. BEARDSLEE, a citizen of the United States, and a resident of Brooklyn, New York, have invented 5
an Improvement in Electric Lights, of which the following is a specification.

The object of my invention is to construct an improved automatic feed or regulator for the carbons of an electric-arc lamp, and this 10 object I attain as more fully described hereinafter.

In the accompanying drawings, Figure 1 is a side view of a lamp embodying my invention; Fig. 2, an enlarged vertical section of the regulating devices; Fig. 3, a plan view of the lamp, and Fig. 4 a sectional plan on the line 15 1 2.

A A is the portion of the frame of the lamp carrying the regulating devices, and through 20 this frame passes vertically the upper-carbon holder B, while the lower-carbon-holder plate E is connected to the frame A by the rods D D', both these rods having an insulated connection with the frame A, and the rod D having 25 also preferably an insulated connection with the plate E, while the rod D' is electrically connected with the plate E.

To the under side of the upper horizontal portion of the frame A are secured the spools 30 of the electro-magnets F F'. In the lower end of the magnet F' is fixed a core, f', of soft iron, which extends to the center of the spool, while in the upper half is a movable core, f, of similar metal, hung to a lever, G, which is pivoted to lugs g on the frame. The center of this 35 lever is slotted to allow of the free passage of the carbon-holder B through it, as shown in Figs. 2 and 4. To the opposite side of this balance-lever is pivoted the upper end of a 40 non-magnetic rod, h, which passes through the hollow fixed core f'', also of soft iron, and extending to the center of the spool. To the lower end of this rod is secured the movable core f', corresponding to the movable core f. 45 To the outer ends of the lever G are connected spiral springs s, having tension-adjusting devices s'. The extent of movement of the lever G and of the movable cores is regulated by suitable screw-stops, T T. The clamping-lever

K for the carbon-holder B rests at one end on 50 the adjusting-screw L, and is held down by a spring, l, and is connected by a link, k, at the other end to a projection on the core f'. The core f is prevented from coming into contact with and sticking to the fixed core f'' by a suitable 55 non-magnetic plug, p, and the core f' is prevented from coming into contact with the fixed core f'' by a shoulder on the rod h. The spools F F' are both wound with thick wire, so as to offer as little resistance as possible to 60 the current, both coils being in the main circuit, as follows: The current, entering at x, passes through the wire 1 to the coil F, coil F', wire 2 to the upper carbon, to the negative carbon, lower-carbon-holder plate E, rod D', 65 and out at y. The adjoining ends of the magnetic cores or poles f f', and also of the poles f'' f', being about midway between the ends of the spools, when a current is sent through the coils these half-cores will be charged with the 70 adjoining ends north and south, so that the movable half-cores will not only be drawn toward the centers by axial magnetism, but the half-cores of each spool will be powerfully attracted toward each other, the lever K will be 75 raised and will grip the upper holder, so as to raise it and the carbon and form the arc for the light. As the carbons are consumed and increased resistance offered to the current, the weight of the upper-carbon holder and lever 80 K will overcome the attraction of the half-cores and the axial magnetism, and the lever K will release the holder B and allow it to drop the requisite distance, when the consequent immediate increase in the current will 85 affect the cores and cause the lever K to grip the holder B. By means of the tension-springs s the balance of the lever and the half-cores in relation to the current can be delicately adjusted, while the extent of movement of the 90 half-cores can be regulated by the screws T.

One of the electro-magnetic coils may in some cases be dispensed with; but I prefer to employ two magnets to operate the lever K. By the use of these half-cores or poles in the 95 regulating-magnets I am enabled to obtain a comparatively powerful effect from a weak current, and thus thick wire may be used for

the coil or coils which are in the main circuit and offer comparatively little resistance to the current.

I do not desire to claim the combination of 5 the hollow fixed core with a movable core having a non-magnetic rod passing through it, as this may form the subject of a separate application.

I claim as my invention—
10 1. The combination of the movable carbon-holder of an electric lamp and a clamp therefore with an electro-magnetic coil having a fixed half-core and a movable half-core, the latter operating the clamp, substantially as described.

2. The combination of a movable carbon-holder and clamp-lever with two electro-magnets in the main circuit, balance-lever C, pivoted between the two magnets and connected 20 to the clamp-lever, said pivoted balance-lever carrying cores at opposite ends acted on by the electro-magnets.

3. The combination of a movable carbon-holder and clamp-lever with electro-magnets

having movable half-cores, balance-lever pivoted at its center, and adjusting-springs connected to the ends of the balance-lever.

4. The combination of the pair of electro-magnets in the main circuit having fixed and movable half-cores, and a clamp-lever connected to one movable half-core, with a balance-lever pivoted at its center and having the movable half-cores pivoted to its opposite ends, one half-core being pivoted directly to the lever and the other through a non-magnetic rod 35 passing through one of the fixed half-cores, all substantially as set forth.

5. The combination of the electro-magnets having movable cores, carbon-holder, and clamp-lever with a balance-lever slotted at the 40 center for the passage of the carbon-holder.

In testimony whereof I have signed my name to this specification in the presence of two subscribing witnesses.

GEO. W. BEARDSLEE.
